UNITED STATES PATENT OFFICE.

WILLIAM HENRY TOWNE HOLDEN, OF NEW YORK, N. Y., ASSIGNOR TO WESTINGHOUSE LAMP COMPANY, A CORPORATION OF PENNSYLVANIA.

METHOD OF VAPORIZING A GETTER IN AN EVACUATED VESSEL.

No Drawing.

Application filed March 23, 1922. Serial No. 546,203.

This invention relates to electrical devices and particularly to discharge tubes of the gas-filled type.

One object of my invention is to provide 5 a method for expeditiously purifying the gas in an electrical-discharge device employing a single electrode.

Another object of the invention is to provide a temporary external electrode in 10 cooperation with a single-electrode tube for the purpose of passing a current through said tube.

This invention is particularly advantageous in connection with a discharge tube 15 having a gaseous atmosphere which will readily glow upon the passage of a slight current therethrough. In tubes of this type, sensitiveness is required in order that differences in potential of only a few hundred 20 volts may be detected and a comparatively high degree of purity of gaseous atmosphere is therefore necessary.

It has not been found convenient or practical to purify the gas previous to its introduction into the tube; inasmuch as pure 25 neon gas is difficult and expensive to obtain, furthermore, great care and time are necessary to introduce such pure gas into a tube without contamination and costly 30 and special apparatus are required. It is therefore desirable to remove deleterious substances from the gas after the tube has been sealed.

In tubes having two electrodes, this is 35 generally accomplished by placing a selected chemical substance or getter material such as magnesium, calcium or the like, upon one or both of the electrodes within the tube prior to the sealing thereof.

40 The getter material is then vaporized by the passage of a current through the tube. While in this state of vaporization, the getter combines chemically with the active gases within the tube or the liberated gases 45 to form nonvolatile compounds or reaction products having low vapor pressure.

In the above mentioned tube which employs two electrodes, this vaporization of the getter material is accomplished by placing the electrodes in circuit with a high-tension source, the action of the electric discharge passing between the electrodes resulting in the getter material being vaporized, as it has been found that the current 55 has a tendency to pass through the getter

material in preference to the electrodes. By reason of this phenomenon, the getter material is heated to its vaporization temperature and a cleaning-up action takes place.

My invention, however, relates particularly 60 to the vaporization of a getter material within a tube employing a single electrode. In a tube of this character, it is necessary to pass sufficient current therethrough to raise the electrode to a temperature 65 high enough to vaporize the chemical substance or to heat the chemical substance to a temperature sufficient for vaporization.

In the present invention, therefore, a temporary or permanent external electrode is 70 provided which may be of any suitable material and shape, as, for instance, a wrapping or cylinder of tin or copperfoil, disposed adjacent the end of the tube opposite to the end in which the internal electrode 75 is disposed. With the aid of this external electrode, a powerful source of high-frequency potential may be employed and sufficient current passed through the tube to heat the electrode or getter material and vaporize 80 the chemical substance.

In practice, an electrode is sealed into a tube in the usual manner and a vaporizable chemical substance is then deposited within the tube, preferably upon the electrode. 85 The tube is then filled with a selected gas and sealed. These steps are common to the manufacture of a discharge tube and my invention relates to the next operation or step which consists in activating the getter material. The tube is then placed in close proximity to the external electrode and a high-frequency potential is applied to the electrodes. It is preferable to employ a high-frequency as, for example, of the order 90 of one million cycles.

A tube, having thus been treated, may be removed from the temporary electrode and another tube disposed adjacent thereto for treatment. It will be readily appreciated 100 that, by my simple and effective method of activating a getter material within a single electrode tube, I overcome various disadvantages which result from the necessity of purifying the gas previous to its introduction into the tube, as would otherwise be necessary.

Although the present invention is particularly described as a method of activating getter material in a discharge tube, it 110

is to be understood that the method may have general application when it is desirable to activate a chemical substance in a hollow body by the passage of a current there-through and where it is not possible by ordinary method to pass sufficient current through the body to heat the electrode or chemical substance to the necessary temperature.

10. What is claimed is:

1. The method of purifying the atmosphere in a discharge tube employing a single electrode which consists in depositing a vaporizable chemical substance upon said electrode, sealing-off said tube, disposing a supplemental electrode adjacent thereto and passing a high-frequency current through said electrodes to vaporize said substance.

2. The method of purifying the gaseous atmosphere in a discharge tube having a single electrode which consists in depositing a vaporizable chemical substance within said

tube, sealing-off said tube, disposing a temporary external electrode adjacent said tube and passing a high-frequency current between said electrodes to vaporize said substance.

3. The method of purifying a gaseous atmosphere in a discharge tube employing a single electrode which consists in depositing on said electrode a quantity of magnesium which is chemically active with respect to deleterious substances within said tube to form non-volatile compounds, exhausting and filling said tube with a gas, sealing-off said tube and disposing adjacent thereto a temporary external electrode and passing a high-frequency current through said electrodes to vaporize said magnesium.

In testimony whereof, I have hereunto subscribed my name this 22nd day of March, 1922.

WILLIAM HENRY TOWNE HOLDEN.
